United States Patent Office.

ALBERT F. ALLEN, OF PROVIDENCE, RHODE ISLAND.

Letters Patent No. 96,862, dated November 16, 1869.

IMPROVEMENT IN HOSE-PIPE NOZZLES.

The Schedule referred to in these Letters Patent and making part of the same

To all whom it may concern:

Be it known that I, ALBERT F. ALLEN, of the city and county of Providence, and State of Rhode Island, have invented a new and useful Hose-Pipe Nozzle.

My invention consists in the use of a flexible-rubber nozzle, and in rendering the same uniformly variable by compression, in order that the size of a stream passing through it may be varied at pleasure to any desirable and useful extent; and I do hereby declare that the following specification, taken in connection with the drawings furnished, and forming a part of the same, is a true, clear, and exact description thereof.

Figure 1 represents, in perspective, one of my hose-pipe nozzles.

Figure 2 represents the same, in vertical section, showing its interior arrangement.

A represents the body of the nozzle. It is provided within its lower end with a female screw, by means of which it is attached to the hose-pipe in the usual manner.

B is a compressor-cap. It is provided with a female screw, fitted to a male screw cut upon the outside of the upper end of the body A. Within the tip of the compressor-cap is an opening, circular in form, somewhat larger in diameter than the largest stream the variable nozzle is capable of throwing. Within this opening is an annular inclined plane, leading from the inner sides of the compressor-cap, to the edges of the opening.

C is a rubber bushing, permanently secured within the top of the body A, in any desirable manner, and

extending sufficiently above to admit of its free compression and expansion.

This bushing should be composed of rubber, tempered to a proper consistency, and vulcanized; and while being sufficiently hard and compact, should also possess the desirable degree of flexibility.

Figures 3 and 4 represent, in top view, my variable nozzle, with the compressor-cap raised and lowered, illustrating the variation between the largest and smallest diameters.

The use of a flexible-rubber bushing in a hose-pipe nozzle in itself secures a smooth and solid stream of water, in addition to its capabilities of compression and variability.

The operation of my nozzle is obvious, as by raising or lowering the compressor-cap the size of the stream is increased or diminished, as may be desired. The rubber expands to its natural size by its own flexibility, and contracts by reason of the uniform compression of the inclined plane within the compressor-cap.

Having thus described my invention,

I claim as new, and desire to secure by Letters Patent—

1. The hose-pipe nozzles lined with a flexible-rubber bushing, for the purposes specified.
2. In combination with a hose-pipe nozzle, the flexible-rubber bushing C, and compressor B, provided with suitable screw-connections and an annular inclined plane, for the purposes specified

Witnesses: ALBERT F. ALLEN.
